Soltau & Polachek
Attorneys

UNITED STATES PATENT OFFICE.

BERNARD SZYMANSKI, OF RAWL, WEST VIRGINIA.

SADDLE STIRRUP.

Application filed January 3, 1922. Serial No. 526,517.

To all whom it may concern:

Be it known that I, BERNARD SZYMANSKI, citizen of the United States, residing at Rawl, in the county of Mingo and State of West Virginia, have invented certain new and useful Improvements in Saddle Stirrups, of which the following is a specification.

This invention relates to saddle stirrups and it has for an object to provide a novel type of stirrups from which the foot of the rider will readily disengage in the event of the latter being thrown.

More specifically speaking, the invention has for an object to provide a stirrup having a detachable section held rigidly in place by the pressure of the rider's foot on the bottom bar of the stirrup.

For further comprehension of the invention, and of the objects and advantages thereof, reference will be had to the following description and accompanying drawings, and to the appended claims in which the various novel features of the invention are more particularly set forth.

Fig. 1 of the drawings is a face view of my improved stirrup.

Fig. 2 is an edge view thereof.

Fig. 3 is a horizontal section on the line 3—3 of Fig. 1.

Fig. 4 is a partial transverse section taken on the line 4—4 of Fig. 3.

Fig. 5 is a detail section on the line 5—5 of Fig. 1.

In constructing my improved stirrups I provide a bottom bar or foot-piece 10 on which the foot of the rider rests and which is connected at opposite ends to an arched yoke comprising a main portion 11 fixed to the bar 10, and a hinged complementary portion 12. The usual slotted head for the attachment of the stirrup strap is formed on the rigid yoke part.

Extending along the foot-piece 10 is a horizontal arm 14 which is hinged near one end as at 15 to the adjacent end of the foot-piece and is accommodated in a longitudinal recess in the latter, this arm being flush at top and bottom with the foot-piece under normal conditions. The arm 14 has formed at its hinged end a short upward projection 15 to which is hinged as at 16, on an axis extending at right angles to the pivotal axis of the arm 14, the lower end of the yoke part 12.

The meeting ends of the two yoke parts

11 and 12 are preferably provided with the interlocking hooked members 17 and 18 which hold them against longitudinal displacement, but permit of rearward or outward swinging movement of the yoke part 12.

Fixed to, and projecting rigidly downward beyond, the lower end of the yoke element 12 is a cam lug 20 having an arched cam recess 21 in its bottom edge. Projecting into this recess is a finger 22 formed on a second arm 23 which is accommodated in a longitudinal slot 24 in the arm 14 and has a common pivotal point with the latter, with which it is flush at top and bottom edges.

Fixed at one end to the bottom of the foot-piece 10 is a flat spring 25 whose opposite end bears on the squared ends of the arms 14 and 23 and holds them in normal position with the interlocking elements 17 and 18 on the yoke sections 11 and 12 resiliently pressed into engagement with one another.

As will be apparent, under normal conditions, the weight of the rider's foot in the arm 14 acts to supplement the spring 25 and hold the yoke element 12 in operative position. In the event of the rider falling, and his foot being caught in the stirrup, the release of the weight from the arms will allow them to swing up when a lateral pull is exerted by the foot of the rider on the stirrup, permitting the hinged section 12 to swing either outwardly or rearwardly and free the rider's foot.

While I have illustrated and described a preferred embodiment of my invention it is to be understood that I do not limit myself to the exact details of construction herein disclosed, and that various changes and modifications might be made therein without departing from the spirit and scope of the invention as defined in the appended claims.

Having thus described my invention what I claim as new and desire to protect by Letters Patent of the United States is as follows:

1. A stirrup comprising a bottom bar, a yoke section fixed to one end thereof, an arm extending along said bar and hinged to the opposite end thereof and having its top face flush with the top face of said bar, and a complementary yoke section having its base portion formed on and rigid with said arm.
2. A stirrup comprising a bottom bar, a

- yoke section fixed to one end thereof, an arm extending along said bar and hinged to the opposite end thereof and having its top face flush with the top face of said bar, and
- 5 a complementary yoke section having its base portion formed on and rigid with said arm, and a spring bearing on said arm to hold the last mentioned yoke section in normal position.
- 10 3. A stirrup comprising a bottom bar, a yoke section fixed to one end thereof, an arm extending along said bar and hinged to the opposite end thereof and having its top face flush with the top face of said bar, a
- 15 complementary yoke section having its base portion formed on and rigid with said arm, a cam element on said arm and a flat spring secured under said bottom bar and bearing on said cam element to hold the last men-
- 20 tioned yoke section in operative position.
4. A stirrup comprising a bottom bar, a yoke section fixed to one end thereof, an arm accommodated in a longitudinal slot in said bar and hinged to the opposite end
- 25 thereof and having a short upward projection at its hinged end, a complementary

yoke section hinged to said projection to swing at right angles to said arm, and means for holding said complementary section against swinging movement on said projec- 30

35 tion.

5. A stirrup comprising a bottom bar, a yoke section fixed to one end thereof, an arm accommodated in a longitudinal slot in said bar and hinged to the opposite end thereof 35 and having a short upward projection at its hinged end, a complementary yoke section hinged to said projection to swing at right angles to said arm, and means for holding said complementary section against swing- 40

45 ing movement on said projection, comprising a second arm extending parallel to said first arm and hinged on a common axis therewith, a finger projecting from said sec- 45 ond arm and engaging an arched cam ele- 45

50 ment on said hinged yoke section, and a spring engaging a cam surface on said sec- ond arm to hold said finger yieldingly en- gaged in said arched cam element.

In testimony whereof I have affixed my 50
signature.

BERNARD SZYMANSKI.
